EX

OR D 2,681

George Jones' DESIGN for TRAY & COFFEE POT.

N°. 2,681.

Patented

Jun 18 1867

Wm. John H. Shumway
A. J. Tibbles

George Jones Inventor
By John E. East

United States Patent Office.

GEORGE JONES, OF SAUGERTIES, NEW YORK.

Design No. 2,681, dated June 18, 1867.

DESIGN FOR A TEA OR COFFEE-POT.

The Schedule referred to in these Letters Patent and making part of the same.

TO ALL WHOM IT MAY CONCERN:

Be it known that I, GEORGE JONES, of Saugerties, in the county of Ulster, and State of New York, have invented a new Design for Tea and Coffee-Pots; and I do hereby declare the following, when taken in connection with the accompanying drawing and the letters of reference marked thereon, to be a full, clear, and exact description of the same, and which said drawing constitutes part of this specification, and represents a side view.

This invention is designed more particularly for that class of tea and coffee-pots known to the trade as the "Eureka," and such as were patented to me April 16, 1867, but as the design is specially for the outward construction, it is alike applicable to other kinds of tea and coffee-pots; and the design consists in the particular external form of the pot, which is of a plain cylinder, A, having formed, at a little distance from its base, a beaded moulding, B, and near the top a similar beaded moulding, C, and provided with a handle, D, upon one side, and a spout, E, upon the other, and a cover, F, all of the form and style shown in the drawing.

What I claim as my design, and desire to secure by Letters Patent, is—

The design for a coffee-pot of the form and configuration shown and described.

GEO. JONES.
